UNITED STATES PATENT OFFICE.

ALFRED L. KOHN, OF NEW YORK, N. Y.

DESIGN FOR A BRUSH.

60,941.

Specification for Design.

Patented May 9, 1922.

Application filed December 7, 1921. Serial No. 520,755. Term of patent 14 years.

To all whom it may concern:

Be it known that I, ALFRED L. KOHN, a citizen of the United States, residing in the city of New York, borough of Manhattan, in the county and State of New York, have invented a new, original, and ornamental Design for a Brush, of which the following is a specification, reference being had to the accompanying drawings, forming a part thereof.

Figure 1 is a plan view of my new design for a brush;

Figure 2 is a side elevation of the same; and

Figure 3 is a bottom plan view of the same.

Referring to the above-mentioned drawings, a brush is shown, the back of which has its greatest breadth near one end and which tapers from this point toward the other end. A groove is provided near the end of the tapered portion and notches are provided at intervals around the curved end of the broadest portion. Grooves are also provided in the sides of the back of the brush. A cross section of the bristles shows them to conform to the shape of the back of the brush.

I claim:

The ornamental design for a brush as described and shown.

ALFRED L. KOHN.
